LOOP TRANSFERRING DEVICE

Harry C. Mills, Rye, N. Y.

Application March 4, 1944, Serial No. 525,027

4 Claims. (Cl. 112—27)

1

This invention relates to the art of knitting and more particularly to the removal of loops or stitches from a knitting machine. In the manufacture of stockings on tubular knitting machines, the stockings are usually removed from the machine and the stitches picked up by hand in order to close the toe. This requires skilled labor and a considerable amount of time to pick up the stitches.

An object of this invention is to provide a device by which the stocking may be transferred from a round shape to a flat shape so that the stitches may be joined together.

A further object is to provide a means by which stitches or loops may be taken from the needles of any circular or flat knitting machine and placed in any desired position for stitching or further operations.

Other objects and advantages of my invention will appear from the accompanying drawings and description.

Referring more particularly to the drawings—

Fig. 1 is a vertical section of my device;

Fig. 2 is a bottom plan view of Fig. 1;

Fig. 3 is a detail view of a section of the locking ring;

Fig. 4 is a plan view of a flexible member adapted to pick up the stitches;

Fig. 5 is a detailed view of the flexible member shown in Fig. 4;

Fig. 6 is a cross sectional view taken on the line 6—6 of Fig. 5;

Figs. 7 and 8 are views showing the way a stitch is removed from the needles to the transfer device;

Fig. 9 is a detailed view showing one set of stitches on the transfer device;

Fig. 10 is a sectional view showing stitches after transfer;

Fig. 11 is a detailed cross sectional view showing the manner in which the transfer member is hinged;

Fig. 12 is a view showing a step in the transfer of the stitches;

Fig. 13 is a further sectional view of an additional step in the transfer;

Fig. 14 is a view showing the final step in the transfer;

Figs. 15 and 16 are views showing the way the transfer is effected mechanically;

Fig. 17 is a plan view of a section of the transfer means;

Fig. 18 is an elevation showing the manner in which the stitches are joined together on the transfer means.

2

As previously stated in knitting stockings on a tubular machine, the stocking when finished hangs on the needles within the annular portion of the machine. My device 15 comprises an annular member 16 which may be provided with a ledge 17 and which is hollow. A locking ring 18 is provided with a tensioned clamp 19 to fix it tightly about the wall 20 of the annular member 16.

10 I provide a pair of flexible tape members 21 and 22 which may be made of flexible steel or any other material. Each of the members 21 and 22 is provided with a series of teeth 23 in the form of points or quills. These points or quills are U-shaped in cross section at their base 25 and taper at their points 26. They may be welded or otherwise fastened to the flexible members 21 and 22. Each of the points or quills 23 is provided with a cutout portion 27 adapted to prevent a stitch from slipping off of the point. Members 21 and 22 are preferably joined together by means of hinges 28 and 29 at either end thereof.

The flexible members are placed around the wall 20 of the annular member 16 and clamped into place with the locking ring 18. The entire device 15 may then be placed over the top of a knitting machine so that each needle 30 registers with a point or quill 23 with the sides of the point engaging the needle as shown in Fig. 7.

30 The stocking 24 may then be pulled upwardly through the center of the device 15 so that each loop of the stocking will be transferred to one of the teeth 23. Before the stocking loops can be removed as described, it is necessary to retract 35 the sinkers and dividers, that is, to release them from holding action. Sinkers and dividers may be released from holding action by means of a slotted ring inside the cylinder which can be controlled in any convenient manner so that the

40 entire stocking may be removed from the machine onto the device 15. The locking ring 18 is loosened so that the members 21 and 22 may be removed therefrom and they are then flattened with their inner sides 40 and 41 facing each other.

45 The stitches are then transferred from the lower member 22 to the upper member 21 in the following manner. Hook means 42 engage the top stitches 43 on the member 22 and draw them in the direction of the arrow 44. As the stitch 50 clears the point 26 the hook moves upwardly as shown in Figure 13 and then rearwardly to deposit the stitch on the teeth or points carried by the member 21. The hook 42 then moves in the direction of the arrow 45 to release the stitches 55 and leave them on the member 21 adjacent to

the stitches 46 carried by the member 21. A sewing needle 50 carrying a thread 51 then passes through the loops in the channel of the point to sew the loops together, thus completing the stocking.

In Figures 15, 16 and 17 I have shown one method of operating the hook 42 although this may be done by any conventional mechanical means such as cams or other mechanism. As shown in Figure 15 the hook 42 is mounted on a bar 55 connected to a pinion 56 engaging the rack 57 on the arm 58. Members 21 and 22 may be locked in position between the bar 60 and the support 61 by means of a cam lever 62 so that the base 25 of the points and needles abuts the bar 60 and the supporting member 61 for securely positioning them in place. The arm 58 moves into position so that the hook 42 engages the stitch 43 and then moves laterally in the direction of the arrow 65. As it clears the lower point 26 bar 55 is rotated thus causing the pinion 56 to rotate on the rack 57 and to turn the hook in a counterclockwise direction as it moves upwardly on the rack with the bar moving upwardly in the direction of the arrow 66. As the pinion turns on the rack the position of the hook 42 is reversed until it passes the point held by the member 21. The arm then moves inwardly to deposit the stitch 43 alongside of the stitch 46 as shown in Figure 16. At this point the movement of the bar 58 is reversed in the direction of the arrow 65 and the hook 42 releases the stitch, thus completing the operation when a suitable needle such as 50 joins the stitches together.

I claim:

1. A loop transferring device including a flexible member having two sides hinged together at both ends, said member being adapted for disposition relative to the needles of a knitting machine, a plurality of concave teeth on each side of said member adapted to engage the needles of a knitting machine and to receive the stitches therefrom, said flexible member being collapsible and adapted to fold flat upon itself so that the teeth of one side thereof are brought near the corresponding teeth on the second side of said flexible member and a hook for each tooth on the one side of said flexible member adapted to engage the stitch on said tooth and to transfer it to the corresponding tooth on the other side of said flexible member.

2. A device for transferring loops including

5 a two piece flexible member hinged together at both ends, said member being adapted for disposition relative to the needles of a knitting machine, and being collapsible and adapted to fold flat upon itself, the one piece thereof upon the other, concave teeth affixed to the outside of said flexible member, said teeth being adapted to receive the needles of said machine and to receive the loops therefrom, and a hook member for each 10 tooth on the first piece of the flexible member for transferring the loop from said tooth to the corresponding tooth on the second piece of the flexible member.

15 3. Means for transferring stitches from a knitting machine including a hinged flexible member, a plurality of concave teeth on said member adapted to engage the needles of said knitting machine whereby stitches may be pulled from said needles onto said teeth, said flexible member being collapsible and being adapted, by means of its hinges, to fold flat upon itself, means adapted to transfer the stitches from one side of said flexible member to the other side thereof whereby said stitches of the one side may be readily joined to the stitches of the other side, means comprising a hook member for each pair of teeth and means for moving said hook member successively into engagement with a stitch on a tooth on one side of the flexible member and then around the end of said tooth and around the end of the corresponding tooth on the other side of the flexible member, at the same time bringing said hook into the same position relative to said corresponding tooth which it occupied relative to the first mentioned tooth, whereby the stitch may be transferred to said corresponding tooth.

20 4. A loop transferring device comprising two sections, each including a flexible, normally straight strip, said strips being hinged together at both ends, a plurality of knitting needle engaging fingers secured to the outside of each said strip, said strips being positionable to align the fingers with the needles, whereby said fingers 25 are adapted to receive the loops therefrom, a ring carrier on which said strips are positioned in circular form, and a hook member for each finger on one strip for removing the loop from said finger and transferring it to the corresponding finger on the other strip, said strips being foldable for operation of the hook member.

HARRY C. MILLS.
